UNITED STATES PATENT OFFICE.

JAMES L. BUGBEE, OF PROVIDENCE, RHODE ISLAND.

MACHINE FOR WINDING SPOOLS.

SPECIFICATION forming part of Letters Patent No. 375,921, dated January 3, 1888.

Application filed April 9, 1887. Serial No. 161,638. (No model.)

To all whom it may concern:

Be it known that I, JAMES L. BUGBEE, of the city and county of Providence, and State of Rhode Island, have invented a new and useful Improvement in Spool-Winding Machines, of which the following is a full, clear, and exact description, reference being had to the accompanying drawings, forming a part of this specification.

10 My invention relates to machines for winding cotton thread onto rotating spools in layers of gradually-increasing lengths as the spools are filled or built up with thread against the angular flanges or ends.

15 In spooling-machines it is desirable to have a machine adapted to readily and efficiently wind spools of irregular forms as well as spools of regular or standard forms. The standard-form spool has the conical flanges or inner 20 faces of the two ends of the same spool of the same angularity relative to the spool-body, whereas the irregular or defective form of spool has the flanges of the two ends of the same spool each of a different angularity relative to the spool-body. To wind a set of spools 25 of standard form it is required to have the traverse-rod carrying the several thread-guides make an increasing uniform traverse—that is, to travel equal distances relative to a 30 certain fixed central point. To wind a set of spools of irregular or defective form—that is, a set in which each spool has the same degree of irregularity—it is required to have the traverse-rod make an increasing variable trav- 35 erse, or to travel different distances relative to a fixed central point.

The objects of my invention are to provide a spooling-machine which may be readily adjusted to wind perfectly spools of standard 40 forms, and again, by an easy regulation, may be adjusted in a ready manner to wind perfectly a set of irregular spools having the same and any degree of irregularity.

To the above ends my invention principally 45 consists in the novel constructions and arrangements of the sliding shaper-carriage and the independently-adjustable shapers, which shape and control the winding, whereby the traverse-rod carrying the thread-guides may 50 have an increasing traverse either uniform or variable; further, of the peculiarly co-operating shaper-carriage and traverse-slide,

whereby the latter serves to advance the former, which automatically limits the traverse of the latter; further, in the reversing-lever and the coacting means for engaging and disengaging the saddles and traverse-changer; also, in a step-by-step mechanism which is actuated indirectly by the traverse-rod for advancing the shaper-carriage; also, in the adjustable means for automatically stopping the traverse-changer when the spools are filled, which means are operated by the traverse-rod; further, of the novel constructions and arrangements of the several coacting devices and the conjoined parts, as hereinafter fully described and claimed.

In the accompanying drawings, illustrating my invention, Figure 1 represents a front elevation of my improved machine. Fig. 2 represents a top plan view of Fig. 1. Fig. 3 represents a rear elevation of a portion of the machine, the spool-spindle and traverse-rod being partly omitted. Fig. 4 represents a sectional view of the machine, taken on line 4 4, 75 Fig. 2. Fig. 5 represents a sectional view of a part of the machine, taken on line 5 5, Fig. 4. Fig. 6 represents a sectional view of a part of the machine, taken on line 6 6, Fig. 4. Fig. 7 represents a sectional view of the end bearing for the spool-spindle, taken on line 7 7, Fig. 2. Fig. 8 represents an enlarged sectional view taken on line 4 4, Fig. 2, and with the actuating-weight for the shaper-carriage removed. Fig. 9 represents an enlarged detail 85 top view of the device for gradually advancing the shaper-carriage and controlling the shipper-shaft. The guides for the carriage are shown broken off and the push-plate in full. Fig. 10 represents an enlarged side view 90 of a thread-guide mounted on the traverse-rod, shown in section. Fig. 11 represents a top view of the shipper-shaft and adjuncts, the tripping-arm, and of the pinion-shaft and trip-stud in section; also portions of the machine-frame A and traverse-slide H. The broken-line position represents the tripping-arm placing the tilting-arm of the shipper-shaft in position to be actuated by the traverse-slide traveling in direction of the arrow, 100 so as to subsequently ship the power-belt.

In the said drawings like letters of reference designate corresponding parts throughout.

Referring to the drawings, A designates the

machine-frame, which, as shown, is composed of two broad upright and parallel pieces connected by a horizontal piece, A'. The posts B B' support bearings in which the spool-spindle E is journaled and turns, and the post C is provided with a bearing in which the traverse-rod F is loosely mounted. The frame and posts are preferably secured firmly to a bed-plate, D, which may be of any preferred form or size. The shaft G is journaled horizontally in the machine-frame, and carries at one end a coupling, e, for the spool-spindle E, and at the other end is provided with a fast pulley, g, by means of which it is rotated. The traverse-rod F extends horizontally through the broad sides of the machine-frame, and is so set therein as to have a free longitudinal movement. Upon the traverse-rod is mounted the traverse-slide, composed of three separate arms, H, (see Fig. 5,) which are arched near the free ends, as shown in Fig. 8, where they are secured together by means of a flat plate, I. The central arm H is provided with a small roller-hanger, J', tracking on a supporting-rod, J, set rigidly across the machine-frame parallel to the traverse-rod. The traverse-changer K is a shaft loosely mounted through and between the sides of the frame parallel to the traverse rod. The traverse-changer is cylindrical, and has the two halves of its length reversely screw-threaded, and is situated within the arches of the arms H of the traverse-slide, and at one end is provided with a loose pulley, k', and a fast pulley, k, by which it is operated. Beneath the right and left hand screw-threaded portion of the traverse-changer K is set a toothed roll, L, upon which are arranged two sets of teeth, each set extending longitudinally of the roll and over one-half of its length, and the two sets being disposed out of alignment, as shown. The ends of the axle of the roll are journaled in the free ends of a U-shaped frame, M, placed nearly horizontally and pivoted upon a fixed shaft, N, running parallel to the roll, and the ends of which are set in the sides of the machine-frame. The ends of frame M rest upon springs m, supported by the machine-frame, for the purpose of affording a necessary yielding action to the roll L. The pawl-plates O (see Fig. 6) are also pivoted upon shaft N, and their free ends rest upon the upper side of roll L, so as to engage each with one set of teeth on said roll. Owing to the alternate arrangement of the two sets of teeth on the roll, it will be seen that while the free end of one pawl-plate is engaged between the teeth of one set the free end of the other pawl lies upon the high point of a tooth on the other set. Directly above the pawl-plates O, and alternating with the three arms H of the traverse-slide, are placed a pair of shifting-arms, P, (see Figs. 5 and 8,) which are pivoted upon the traverse-rod F. The shifting-arms are constructed of two slotted parts, adapted to be adjusted on each other to increase or diminish the lengths of the arms. The under sides of

the free ends of the arms P are provided with rollers p', resting each upon one of the pawls O. The upper sides of the ends of the arms P each carry a saddle, p², screw-threaded on the upper concave face, either right or left handed, in order to engage and mesh with the respective halves of the traverse-changer K. From this construction it will be obvious that when one of the pawl-plates O is raised upon the high point of a tooth of one set on roll L the other pawl O will be depressed between two teeth on the other set of said roll, and by virtue of this action the shifting-arms P will be alternately engaged and disengaged with the traverse-changer K by means of the saddles p² being elevated and depressed by the device described. The saddles p² are right and left hand screw-threaded to cause each to conform with its coacting half of traverse-changer K, and hence if the former saddle be engaged with traverse-changer K the rotation of the changer will cause the shifting-arm P to travel to the right and carry the traverse-rod F in that direction, and if the latter saddle be engaged with said changer its rotation will serve to move the other shifting-arm P to the left, and likewise the traverse rod F. In these reverse motions the traverse-changer runs in the same direction at all times. Each saddle comes into engagement with the traverse-changer at the center of the latter and works along the changer toward the sides of the machine-frame, and when one shifting-arm has completed its traverse the attached saddle is automatically thrown out of engagement, and the saddle of the other arm is thrown into engagement, with the changer in order to reverse the traverse of the traverse-rod F. The means whereby this is accomplished will now be described. The reversing-lever Q (see Fig. 3) is a three-branched Y-shaped body pivoted near the branch on a pivot, q, fixed on plate I. Near the end of each of the branches of lever Q is arranged a spring-actuated click or pawl, q', (see Fig. 8,) suitably set in a cylindrical body, as shown. The clicks q' are kept in constant engagement with the roll L, and the reversing-lever Q may be rocked on its pivoted bearing q, so that the engaged roll L will receive a step-by-step motion in the direction of the movement of the hands of a clock as viewed from Fig. 8. In order to rock or reverse lever Q on its bearings, I employ a pair of adjustable shaper-stops, a', to trip the upper end thereof. The upright standards A² are secured upon base-plate D, and a is a cylindrical bar set rigidly across from said standards parallel to the traverse-changer K. The shaper-stops a' are set, by means of an eye therein, on bar a, and can be slid in either direction on said bar. The trip-collar R is also loosely mounted on bar a and slides thereon between the two shaper-stops a', which thereby limit the travel of said collar.

The stem of the Y-shaped reversing-lever Q has the end forked, as shown clearly in Fig. 8. In these forks are longitudinal slots, opposite

and parallel, in which work loosely the fixed screws r , set at opposite points on trip-collar R, which lies in the fork of the stem of lever Q. Owing to this construction, the reversing-lever Q is reversed by virtue of the shaper-stops a' being fixedly set at predetermined points and allowing the trip-collar a definite traverse, and as the lever Q is carried by plate I while the latter is moved by the traverse-rod F through the medium of the shifting arms P, their saddles, and the traverse-changer K, the trip-collar will be accordingly slid on rod a , and will be tripped by either one or the other of the shaper-stops a' , thereby tilting lever Q and actuating roll L to operate the pawls O, which serve to engage one saddle and disengage the other, so as to reverse the traverse of the traverse-rod F in an obvious manner.

Since the shaper-stops a' shape and control the winding of the spools by graduating the length of the successive layers of thread, it is necessary that the said stops should be adjustable toward and away from each other, and that they then be governed to make a gradually-increasing adjustment or divergence, in order to regulate the traverse of the traverse-rod carrying the thread-guides.

In winding spools of standard forms the shaper-stops are predeterminedly set at points equidistant from a certain fixed central point, according to the size of the set of spools to be wound, and the stops are governed to make increasing uniform adjustment or divergence to accord with the form of the spools; but it will be readily seen that any means which is only capable of a uniform degree of gradual adjustment of the shaper-stops would not be capable of producing a perfect winding upon a set of irregular or defective spools having the same irregularity each. Thus to accomplish the winding of spools of irregular forms the shaper-stops must be controlled to have an increasing variable adjustment or divergence—that is, the movements of the stops away from a fixed central point must be of different distances in order to build the thread against the spool-flanges having different singularities.

In order to render spooling-machines capable of perfectly winding not only regular but also irregular forms of spools, I have devised the following adjustment, and will proceed to describe the same as embodied in the preferred construction shown.

Upon the opposite ends of the side pieces of frame A from the standards A^2 are placed two posts, A^3 , connected by a fixed bar, a^2 , and the upper ends of standards A^2 are connected by means of the two fixed bars a^3 , lying in the same plane and apart, just above bar a , parallel therewith. The two guides S are set at right angles across the bars a^2 and bar a^3 , upon which they are fixed by fast collars a^4 , set on said bars, so that said guides lie midway between the broad sides of frame A. The shaper-carriage T (see Fig. 2) slides to and fro on guides S, and is a T-shaped body provided

with a flange, t , extending downwardly at right angles thereto, and which works between said guides. The slot t^5 is formed in the flange t to allow it to work over the bars a^3 . The curved slots t^2 are formed symmetrically, one in each side of the cross-head of the T-shaped carriage T, and in said slots work the binders u , which may be moved therein and clamped securely at any points. The binders u consist each of a screw-threaded shank having a head and of a thumb-nut working in the shank, as will be understood by referring to the drawings. Near the end of the stem of carriage T is fixed a cross-piece, t' , at corresponding points on which are swiveled the corresponding ends of the shapers U. The other ends of said shapers are each provided with a binder, u , working in the guideway u' of the carriage. The shapers U are flat straight bodies, and from their arrangement and construction it will be evident that they can be readily adjusted relative to the central line of length of carriage T and relative to each other—that is, they may be both set at the same angles with said line, or may each be set at a different angle therewith. Of course the shapers are adjusted and rigidly set by means of binders u being adjusted and clamped. In each guideway u' works a guide-pin, v , formed one on each of the stop-carriers V, which are flat three-cornered pieces traveling freely on bars a^3 , as shown. The stop-carriers V are adjustably connected one with each of the shaper-stops a' by means of the screw-stems a^5 , fixed to said stops, and the adjusting-nut a^6 , working on the stems, whereby the stops may be spaced as required by the varying sizes of spools to be wound. By virtue of this construction, if the shapers be set and fixed at equal angles relative to the carriage, as shown in Fig. 2, and the shaper-carriage be slid toward the back of the machine, the controlled shaper-stops, predeterminedly set, will be slid apart, as described, by the guide-pins in a uniform manner, and each will travel equal distances. On the other hand, if the angles of the adjustment of the shapers be different relative to the carriage, the sliding of said carriage will cause the shaper-stops to diverge or move away from each other in a variable manner, and each will travel different distances proportionate to the difference of adjustment of their controlling shapers, respectively.

The figures show the machine as set at one limit of traverse of the traverse-rod F and the coacting parts, and necessarily said rod will make its least traverse for winding that layer before the shaper carriage begins to slide, and will make gradually-increased traverses as the carriage slides backward, and its greatest traverse will occur when the carriage ceases to move and the last layer of thread is to be laid.

In order to effect the gradual movement of the shaper-carriage necessary to the required variation in the position of the shaper-stops a' , I employ the following arrangement: Upon

one side of a projection of flange t is screw-set a rack-bar, t^3 , (see Figs. 5 and 8,) disposed parallel to the length of carriage T. The pinion-wheel w is in mesh with rack-bar t^3 , (see Figs. 5 and 8,) and is keyed upon a vertical rotary shaft, W, the lower end of which is journaled in a stand, A⁴, set on cross-piece A' of the machine-frame, and the upper end is journaled in a bracket, s, (see Fig. 2,) fixed upon one of guides S. Below pinion w (see Fig. 9) the ratchet-wheel w' is keyed upon shaft W, and between said pinion and ratchet is loosely mounted the movable arm X on said shaft. The outer end of arm X is provided with an anti-friction roller, and carries also a pawl, x , which is kept in constant engagement with ratchet w' by means of spring x^3 , set between the pawl and arm X. The arm X is maintained in contact with push-plate h' (see Fig. 9) by means of spring x' , lying between said arm and the adjacent guide S, so that its anti-friction roller bears against the edge of said push-plate. The push-plate travels in company with the traverse-rod by means of being adjustably mounted on bracket h , carried upon the traverse-slide, which is actuated by said traverse-rod. Thus, as the traverse-rod travels toward the left-hand side of the machine in the figures, the traverse-slide carries the beveled edge of push-plate h' against the anti-friction roller on the movable arm X, and so forces the same outwardly and causes the pawl x to rotate the engaged ratchet w' , and thereby advance the shaper-carriage through the medium of the shaft W and pinion w in mesh with rack-bar t^3 . This gradual advance of the shaper-carriage is sufficient to move the shaper-stops away from each other the required distances to increase the length of the traverse of the traverse-rod for the succeeding layer of thread. When the push-plate h' has traveled away from the arm X, the same will recede and allow its pawl to engage with the next tooth to be subsequently advanced, as described. The shapers being once adjusted, the machine will automatically operate the shaper-stops to control the traverse of the traverse-rod to accord with said adjustment of the stops.

The operation of the sliding or advancing device for the shaper-carriage is made against the action of a weight, y, attached to one end of a cord or chain, j, leading over a pulley, s', set between guides S, the other end of said chain being attached to a forward extension of flange t of the shaper-carriage. Thus the tendency of the weight y is to draw the carriage toward the front of the machine, while that of the pawl-and-ratchet device is to draw said carriage toward the rear of the machine. When the pawl-and-ratchet device has drawn the carriage to the full limit of travel, the pawl is to be disengaged from its ratchet by pressing on handle x^2 of the pawl, whereupon the weight y will automatically return the carriage to the front of the machine.

In order that the machine may automati-

cally cease running when the spools are wound full, the ratchet-wheel w' (shown enlarged in Figs. 8 and 9) is formed with a set of sockets 70 in the body of said wheel for the insertion of the movable trip-stud w^2 . Since every action of the push-plate h' upon the ratchet w' advances the same one tooth in rotation, the trip-stud may be placed in a predetermined socket, 75 so that when the machine is to be stopped the stud will trip a tripping-arm, Z, (shown enlarged in Fig. 11,) and will effect the shifting of the driving-belt (not shown) from the fast to the loose pulley, k and k', respectively. The 80 tripping-arm is pivoted on shaft W just below ratchet w' . The trip-stud w^2 is moved in the direction of the arrow, Fig. 11, and trips the arm Z into the broken-line position. (Shown in said figure.) This tripping arm Z engages 85 the tilting-arm Z', mounted on the shipper-shaft Z², provided with a shipper, z, and journaled in machine frame A. When the tilting-arm Z' is thrown over in the direction of the arrow by the arm Z, it lies in the path of the moving traverse-slide and is struck by an arm, H, thereof, moving as per the arrow adjacent, and is then borne along with the slide until the belt is shipped, by virtue of the shipper-shaft being carried lengthwise on its 90 bearings in the direction of the arrow parallel therewith. When the machine is to be started running again, the shipper is forced in by hand, the tilting-arm Z' being retracted by spring z'. 95

The thread-guides, one of which is shown enlarged in Fig. 10, consist each of an arm, C', having an eye therein, by means of which it is set loosely on traverse-rod F. To the pin C² on arm C' is fixed the end of a coil spring, 100 c, the other end of said spring being fastened upon the binding-collar c', which is adjustable on rod F by means of the set-screws c'', and is set fast in position, this permitting of the arm C' being tilted on its bearings with a spring-pressure, the collar c' remaining fast. The number of thread-guides may be increased or diminished to accord with the number of the spools 8 to be wound during each run of the machine. 115

The post B carries a bearing, b, for the spool-spindle E, and this bearing has a hinged cover, b', by raising which the spindle may be removed. The post B' carries a peculiar separable bearing, b''. (Shown clearly in section 120 in Fig. 7.) This bearing consists of an eye to receive an internally screw-threaded tube, b³, within which works a screw-bar, b⁴, provided with a jam nut, b⁵. The inner end of tube b³ is enlarged to receive a socket, b⁶, which is held by screws b', projecting into an annular groove formed around the socket b⁶, and arranged to receive the end of spindle E, said spindle having a groove to receive a spline on the interior of socket b⁶. The perforation b¹⁰ 125 leads from the outside of the tube b³ to the space formed about the inner end of socket b⁶ and allows the oil to be fed to the socket-bearing. By this means the oil is fed between the 130

end of the tube b^3 and socket b^6 and does not reach the end of spindle E. The tube b^3 is held in eye b^2 by a screw, b^8 . The bearings of posts B, B', and C are provided with stems extending down in said posts and held adjustably therein by binding-screws b^9 , the purpose of mounting the bearings adjustably upon said posts being to facilitate the leveling of the spool-spindle and traverse-rod.

10 The general operation of the machine is as follows: The spool-spindle is first supplied with the desired number of empty spools, there being a corresponding number of thread-guides mounted on the traverse-rod. The 15 shaper-carriage is placed at the forward limit of travel upon the guides. The shapers are then adjusted at the same or different angles to the center line of length of the shaper-carriage, according as the spools are of a regular 20 or irregular form, and in this position they are firmly set by means of the binders. The machine is started and the traverse-rod travels in one direction by means of one shifting-arm, and is then reversed and travels in the opposite 25 site direction by means of the other shifting-arm. The motion of the traverse-rod serves to slide the shaper-carriage on its guides, through the mediums of the push device and the step-by-step mechanism, and thereby increase 30 the space between the shaper-stops for the trip-collar, controlling the reversing-lever, to travel in, and so the device for engaging and disengaging the shifting-arms is governed and the traverse-rod regulated. Thus the machine 35 works on itself automatically until the required number of layers have been wound, when the predeterminedly-set trip-stud affects the belt-shipping device to stop the machine. The spool-spindle is now detached and the 40 wound spools removed therefrom, after which the shaper-carriage is set back to its starting-place and the spindle with a fresh set of spools is replaced in the machine and the above described operation repeated.

45 There may be various modifications made in the principal parts of the machine here shown and described without substantially departing from the spirit of my invention as herein described and claimed.

50 Having thus described my invention, I claim as new and desire to secure by Letters Patent—

1. In a spool-winding machine, the combination, as hereinbefore set forth, with a belt-shipping device and a traverse-rod having 55 actuating means, and also means for engaging the belt-shipping device when the latter is thrown into action, of a sliding shaper-carriage and a step-by-step operating mechanism, substantially as described, for said carriage, 60 said mechanism provided with adjustable means for tripping the belt-shipping device at a predetermined time and moving the said shipping device so as to be acted on by said means of the traverse-rod to ship the belt, substantially as herein described.

65 2. In combination, a traverse-changer and actuating means therefor, an endwise-moving

traverse-rod, a pair of shifting-arms engaging said changer, said arms pivoted on and actuating said traverse-rod, a pair of pawls, each 70 one coacting with one of said arms, a rotary toothed roll provided with two sets of longitudinally-disposed teeth out of alignment and engaged by said pawls, a pair of shapers, a sliding shaper-carriage carrying said shapers, 75 means, substantially as described, whereby said shapers are held upon the carriage with capacity for independent adjustment, and a reversing device controlled by said shapers and actuating said toothed roll. 80

3. In combination, a traverse-changer and actuating means therefor, an endwise-moving traverse-rod, a pair of shifting-arms engaging said changer, said arms pivoted on and actuating said traverse-rod, a pair of pawls 85 coacting each with one of said arms, a rotary toothed roll provided with two sets of teeth disposed longitudinally thereon out of alignment and engaged by said pawls, a pair of shapers, each provided with a sliding shaper-stop, a sliding shaper-carriage, a traverse-slide, means, substantially as described, whereby said shapers are held upon the carriage with capacity for independent adjustment, mounted on and actuated by said traverse-rod, and a reversing device secured upon said slide, said device controlled by said shaper-stops and engaging and actuating said toothed roll, whereby 90 said shifting-arms may be operated to limit the traverse of the traverse-rod according to the adjustment of the shapers. 100

4. In combination, a traverse-changer and actuating means therefor, an endwise-moving traverse-rod provided with thread-guides, a pair of shifting-arms engaging said changer, 105 said arms pivoted on and actuating said traverse-rod, means for engaging and disengaging said shifting-arms and changer, a traverse slide mounted on and actuated by said traverse-rod, a reversing-lever pivoted on said slide and governing said engaging and disengaging means, a pair of shapers, each provided with a sliding shaper-stop, and a sliding shaper-carriage carrying said shapers, whereby the 110 traverse of the traverse-rod may be controlled. 115

5. In combination, a traverse-changer and actuating means therefor, an endwise-moving traverse-rod, a pair of shifting-arms engaging said changer, said arms pivoted on and actuating said traverse-rod, a pair of pawls coacting 120 one with each of said arms, a rotary toothed roll provided with two sets of longitudinally-disposed teeth out of alignment and engaging said pawls, a traverse slide secured upon and actuated by said traverse-rod, a reversing-lever pivoted upon said slide and actuating said roll, a pair of shapers, each provided with a sliding shaper-stop for said lever, and a sliding shaper-carriage carrying said shapers, whereby 125 the traverse of the traverse-rod may be regulated and reversed. 130

6. In combination, a traverse-changer and actuating means therefor, an endwise-moving traverse-rod, a pair of shifting-arms engaging

5 said changer, said arms secured on and actuating said traverse-rod, means for engaging and disengaging said arms and changer alternately, said means consisting in a rotary toothed roll provided with two sets of longitudinally-disposed teeth arranged out of alignment, and a pair of pawls engaging said teeth and the arms, a traverse-slide mounted on and actuated by said traverse-rod, a reversing-lever pivoted on said slide and actuating said means, a pair of shapers, each provided with a sliding shaper-stop for the reversing-lever, a sliding shaper-carriage carrying said shapers, and means intermediate between said traverse-rod and carriage for sliding the carriage, said means actuated by the movement of the traverse-rod, whereby the carriage may be moved automatically to adjust the shapers, and thereby limit the travel of the traverse-rod, substantially as described.

7. In combination, a sliding shaper-carriage provided with a rack-bar, a pinion in mesh with said rack-bar and keyed upon a rotary shaft, an adjustable tripping device secured upon said shaft, a trip arm engaged by said device, a shipper-shaft provided with a tilting-arm engaged by said trip arm, an endwise-moving traverse-rod and actuating means therefor, and provided with means for engaging said tilting-arm, and means for rotating said pinion-shaft, whereby the carriage may be moved and the trip-arm actuated by the tripping device.

8. In combination, a traverse changer and actuating means therefor, an endwise-moving traverse-rod, a pair of shifting-arms engaging said changer, said arms secured on and actuating said traverse-rod, means for engaging and disengaging said arms and changer alternately, a traverse-slide mounted on and actuated by said traverse-rod, a reversing-lever pivoted on said slide and actuating said engaging and disengaging means, a sliding shaper-carriage provided with a rack-bar, a pair of shapers mounted on said carriage and each provided with a sliding shaper-stop for controlling the throw of said reversing-lever, a pinion-wheel in mesh with said rack-bar and keyed on a rotary shaft, an adjustable tripping device secured upon said shaft, a trip-arm engaged by said device, a shipper-shaft provided with a tilting-arm engaged by said trip-arm, said traverse-rod provided with means for engaging said tilting-arm and means for rotating said pinion-shaft, and means, substantially as described, whereby said rotating means is controlled by said traverse-rod, said shapers predeterminedly adjusted so that the travel of the traverse-rod may move the carriage and automatically adjust the shapers, thereby regulating the throw of the reversing-lever to change and limit the traverse of the traverse-rod and to operate the shipper-shaft.

9. In combination, an endwise-moving traverse-rod, means for actuating the same, and a push device mounted on said rod, a sliding shaper-carriage provided with a rack-bar, a

pinion-wheel in mesh with said rack-bar and keyed upon a rotary shaft, a ratchet-wheel mounted upon said shaft, a pawl engaging said ratchet, and a swinging arm carrying said pawl and actuated by said push device, substantially as set forth.

10. In combination, an endwise-moving traverse-rod and actuating means therefor, a push device mounted on said rod, a sliding shaper-carriage provided with a rack-bar, a pair of shapers mounted on said carriage, a pinion-wheel in mesh with said rack-bar and keyed upon a rotary shaft, a ratchet-wheel keyed upon said shaft, a movable arm mounted on said shaft and provided with an anti-friction roll and a spring actuated pawl, said arm engaged by said push device and said pawl engaging said ratchet, said ratchet provided with an adjustable trip-stud and sockets therefor, a trip-arm mounted upon said shaft and engaged by said stud, and a shipper-shaft provided with a tilting-arm, said traverse-rod provided with means for engaging said tilting arm, substantially as described.

11. In combination, a pair of fixed parallel guide-rods, a pair of stop-carriers sliding on said rods and provided with guide-pins, shapers engaging said guide-pins and means for moving said shapers, a stop secured adjustably to each of said carriers by a screw-stem, said pair of stops sliding on a fixed guide-rod disposed parallel to the other said rods, a trip-collar sliding on the guide-rod carrying said stops and traveling between said stops, a rotary traverse-changer consisting of a bar having the two halves of its length reversely screw-threaded, means for actuating said changer, a traverse-rod lying parallel to said changer-bar and moving endwise and provided with thread-guides, a pair of shifting-arms pivoted upon said traverse-rod, said arms provided with concaved screw-threaded saddles, each one engaging with a half of said changer, a rotary toothed roll having yielding bearings and provided with two sets of longitudinally-disposed teeth out of alignment, a pair of pawl-plates engaging one with each of said sets of teeth and actuating said shifting-arms, a traverse-slide secured upon said traverse-rod and consisting of arched arms secured together by a plate and supported by a hanger traveling on a rod, and a reversing-lever provided with three branches and pivoted upon said slide, one branch of said lever attached to said trip-collar, the other two branches of said lever provided each with a spring-click engaging each with one of the sets of teeth on said toothed roll, substantially as set forth.

12. In combination, a sliding shaper-carriage and a rack-bar fixed thereto, a pinion-wheel keyed upon a rotary shaft and in mesh with said rack-bar, a ratchet-wheel keyed on said shaft, a movable spring-acted arm mounted on said shaft and provided with an anti-friction roll and a spring-pawl, said pawl constantly engaging said ratchet, an endwise-moving traverse-rod and actuating means

therefor, a traverse-slide mounted on and actuated by said traverse-rod and consisting of arched arms secured together by a plate, said slide supported at the outer end by a hauger 5 traveling on a fixed rod, and a push-plate mounted on said slide and actuating said movable arm, substantially as described.

13. In combination, a traverse-changer and actuating means therefor, an endwise-moving 10 traverse-rod, shifting-arms provided with saddles intermediate between said changer and rod for alternately actuating said rod to and fro, and means, substantially as described, for engaging and disengaging said arms with the traverse-changer, a traverse-slide mounted on said 15 traverse-rod and actuated thereby, a reversing-lever pivoted upon said slide and engaging and actuating the means for engaging and disengaging the said arms with the traverse-changers, a shaper-carriage provided with the step-by-step actuating device, substantially as described, a pair of shapers provided with guideways mounted on said carriage, a pair of sliding adjustable shaper stops having a support 20 and working one in a guideway of the respective shapers, and means for controlling the positions of said stops from the shapers, said stops engaged by said reversing-lever controlled thereby, whereby the traverse of the 25

traverse-rod may advance the carriage and 30 change the adjustment of the shaper-stops to limit the traverse of the traverse-rod.

14. In combination, a post, a socket-eye, and means whereby said socket-eye is adjustably mounted on said post, an internally-screw-threaded tube provided with an enlarged end and set through said socket-eye, a screw-bar working in said screw-thread of the tube and provided with a jam-nut abutting against the smaller end of said tube, a socket fitting in the 35 enlarged end of said tube, and provided with means for holding the same therein against longitudinal movement and permitting revolution thereon, said socket provided with a spline, the slotted spindle set in said socket, 40 and the said spline taking in the slot thereof, 45 substantially as described.

15. In combination, the spool-spindle and the bearing composed of the following elements: the socket-eye b^2 , the internally-screw-threaded tube b^3 , the screw-bar b^4 , provided with the jam-nut b^5 , and the socket b^6 , provided with set-screws b^7 , substantially as described.
